United States Patent Office

Des. 211,525
Patented June 25, 1968

211,525

INDUSTRIAL ULTRASONIC WELDER

Channing W. Gilson, Los Angeles, and John E. Larrison,
Costa Mesa, Calif., assignors to Hughes Aircraft Com-
pany, Culver City, Calif., a corporation of Delaware

Filed Jan. 16, 1967, Ser. No. 5,418

Term of patent 14 years

(Cl. D26—1)

Fig. 1.

Fig. 2.

Fig. 3

FIGURE 1 is a perspective view of an industrial ultrasonic welder showing the new design;

FIGURE 2 is a side elevational view;

FIGURE 3 is a top plan view with portions omitted for ease of illustration.

The dominant features of our design reside in the portions shown in full lines.

We claim:

The ornamental design for an industrial ultrasonic welder, substantially as shown and described.
